GEORGE KOCH, OF SHELTON, CONNECTICUT, ASSIGNOR TO SIDNEY BLUMENTHAL & COMPANY, OF NEW YORK, N. Y., A CORPORATION OF NEW YORK.

WARP STOP-MOTION FOR LOOMS.

1,047,080.

Specification of Letters Patent. Patented Dec. 10, 1912.

Application filed August 15, 1911. Serial No. 644,199.

To all whom it may concern:

Be it known that I, GEORGE KOCH, a subject of the Emperor of Germany, and resident of Shelton, in the county of Fairfield 5 and State of Connecticut, have invented a new and useful Improvement in Warp Stop-Motions for Looms, of which the following is a specification.

My invention relates to a warp stop motion for looms, with the object in view of providing effective means for stopping the action of the loom when for any cause a warp thread breaks.

My present invention is illustrated in connection with what is known as the "Tonnar" loom for weaving a double pile fabric, but I do not wish to limit it to this particular type of loom, as it may be successfully employed in connection with looms of various well known types.

In the accompanying drawings, Figure 1 is a view in side elevation, partly in section, of so much of a loom as will serve to show the practical application of my invention. 25 Fig. 2 is an enlarged partial plan view of the same. Fig. 3 is an enlarged partial vertical section of the same. Fig. 4 is an enlarged plan view in detail of the tripping mechanism. Fig. 5 is a view of the same in 30 elevation, partly in section, and Figs. 6, 7 and 8 illustrate in side elevation, modified forms of the contact pieces for completing the electric circuit.

The loom frame is denoted by 1, the gang 35 of heddles by 2, the warp beams by 3 and 4, the lay beam by 5, the control lever by 6, the rocking lever for effecting the stopping of the machine, by 6*, the cam for operating said lever by 7, the hook on one arm of 40 said lever by 8, and the rocking weft stop fingers by 9. These parts so referred to, may be of any well known or approved form, such, for example, as shown in the Tonnar Patent No. 716352 dated December 45 16, 1902.

For applying my present invention in a practical manner, uprights 10 and 11 are fixed to a suitable horizontal support 12 and are provided with U-shaped brackets 13, 14, 50 secured to the respective uprights at the middle portion of their bight, one arm of each of the said brackets being projected downwardly farther than the other arm. The arms of these brackets 13, 14, are each 55 provided with elongated slots, those in the

shorter arms being denoted by 15, 16, and those in the longer arms being denoted by 17, 18. Horizontal boxes 19, 20, extending the width of the loom between the brackets 13, 14, are fitted at their ends, the one to rise 60 and fall to a limited extent within the slots 15, 16, and the other within the slots 17, 18. These boxes are suspended at their opposite ends from hangers 21, 22, connected by a band 23 passing over a pulley 24 arranged 65 to be rocked at the proper time with respect to the rocking of the heddles to maintain the proper tension upon the warp threads 25, 26. In the present instance, this is accomplished by means of a belt 27 leading from 70 a pulley 28 on the shaft 29 which rocks the heddles, to a pulley 30 suitably supported from the top frame of the loom and connected by a belt 31 with the shaft which carries the pulleys 24. It is to be understood that a pair of hangers similar to 21, 22, is employed to suspend the opposite ends 75 of the boxes 19, 20.

Within each of the boxes 19, 20, there are provided on a rod 32 in the box 19 and on a rod 33 in the box 20, a series of contact pieces denoted by 34, and each provided at its upper end, which projects slightly through the top of the box, with an eye 35 through which a warp thread leading over 80 the top of the box, passes, as it leads from the warp beam to the heddles. Along the lower portion of the box, there is fixed a rod 36, insulated from the box by suitable insulation 37, the rod 36 being in position 85 to contact with the toe of any one of the contact pieces 34 when the latter is allowed to tilt into an abnormal position, shown clearly in Fig. 3, by the breaking of a warp thread. As long as the warp thread remains intact, 90 the contact piece 34 will be held by the warp thread in a position sufficiently upright, as clearly shown in Fig. 3, to carry its toe out of contact with the rod 36.

The rod 36 is electrically connected, for example, by a wire 38, see Fig. 2, with one pole of a battery 39. The opposite pole of the battery is connected by a wire 40 with one pole of an electro-magnet 41, the opposite pole of the electro-magnet being connected with some part of the machine which is in electrical contact with the part of the machine which is electrically connected with the rod 32 on which the contact pieces 34 are pivoted.

The rod 36 connected with the box 19, is electrically connected by a wire 42 with the corresponding insulated rod on the box 20, and thence by the wire 38 to the battery, 5 and the boxes 19 and 20 may be electrically connected as by a wire 43, so that the rods 32 and 33 may be in electrical contact and the connection of either or both of them with some part of the machine by which the 10 current may be carried to the pole of the electro-magnet 41, will complete the circuit when the contact piece 34 is tilted into position to connect the rod 32 or 33 with the insulated rod 36 on the box 19 or its corresponding rod on the box 20.

The armature 44 of the electro-magnet 41 is on one arm of a lever pivoted at 45, the opposite arm of the lever being provided with an abutment 46 which rests 20 against the upper arm 47 of a weighted lever pivoted at 48. The said arm 47 of the weighted lever is provided with a projection 49 connected with a link 50, attached to a pull rod or cord 51, extending upwardly 25 and connected with the end of a pawl 52, see Fig. 5. The pawl 52 is pivoted on a pintle 53, the latter supported on a bar 54 held in a bracket arm 55, which in turn is secured on a horizontal rocking arm 56, pivoted at 56* to a bar on the main frame. The 30 bar on the main frame is provided with an elongated slot 57, and an offset notch 58 in which the control lever 6, which projects upwardly through the slot 57, is held to 35 hold the loom in action. When the arm 56 is swung horizontally to force the control lever out of its retaining notch 58, into the slot 57, an actuating spring, not shown, on the control lever will throw it along the 40 slot 57 into position to throw the loom out of action.

The pawl 52 is arranged to coact with the hook 8 on the rocking lever 6*, and is held out of contact with the hook on said rocking lever and in contact with the hook by 45 a rolling weight 59 housed in a tube 60 fixed to the top of the pawl 52. In the position shown in Fig. 5, the rolling weight 59 is in a position to hold the nose of the pawl 52 elevated and out of position to engage the hook 8 as the latter is reciprocated back and forth toward and away from the heddles during the operation of the loom. When, however, the pawl 52 is forcibly tilted down 50 into the position shown in dotted lines in Fig. 5, the rolling weight 59 will pass to the opposite end of the tube 60 and hold the said pawl down in position to engage the hook 8. When the hook 8 catches the pawl 52, it will carry the pawl and the pivotal support of the pawl, as well as the bar 54 and its support, bodily to the right as the drawing is held, thereby forcing the control lever 6 out of the notch 58 and allowing it to travel along the slot 57 under the

action of its spring to throw the loom out of action.

In operation, so long as the warp threads remain intact and hold the contact pieces 34 out of engagement with the insulated rod 36 and its corresponding rod on the box 20, the hook 8 will work idly so far as the warp threads are concerned, but when for any cause a warp thread breaks, its contact piece will promptly tilt into engagement 75 with the rod 36 or its corresponding rod on the box 20, thereby closing circuit through the electro-magnet 41, and by the series of operations already fully described, the control lever 6 will be promptly thrown into 80 position to throw the loom out of action.

The contact pieces 34 may assume various forms other than that shown in Figs. 1 to 5 inclusive; for example, as shown in Fig. 6 the eye, denoted by 61, may be open or 85 as shown in Fig. 7, the eye, denoted by 62, may be open, and also the hole through which the pivot rod 32 extends may be open, or as shown in Fig. 8, the eye may be closed and the hole through which the rod 90 32 extends open, as shown at 63.

What I claim is:

1. In a stop motion for looms, a plurality of boxes mounted to rise and fall and adapted to receive the warp threads on 95 their upper sides, means for alternately raising and lowering the boxes, a series of contact pieces pivoted in each of the boxes, one contact piece for each warp thread, and each having an eye portion which projects 100 through the upper side of the box to receive a warp thread, rods insulated from and carried by the boxes in position to be engaged by the contact pieces when the latter are free to tilt, the warp threads being 105 arranged when intact to hold the contact pieces out of contact with the insulated rods, an electric circuit including the said insulated rods, contact pieces and an electromagnet, a loom control lever and means under 110 the control of the electromagnet for throwing the control lever in position to stop the loom when the electromagnet is energized.

2. In a warp stop motion for looms, an electric circuit including an electro-magnet, 115 means under the control of the warp threads for energizing the magnet when a warp thread breaks, a reciprocating hook, a pawl in position to engage the hook, a shifting weight for holding the pawl in and out of 120 engagement with the hook, means under the control of the electro-magnet for operating the pawl, a loom control lever and means connected with the pawl for throwing the loom control lever into position to 125 stop the loom when the pawl is thrown into engagement with the hook.

3. In a warp stop motion for looms, a rocking pawl, a shifting weight for holding the pawl in different tilted adjustments, 130

means under the control of the warp threads for tilting the pawl, a reciprocating hook arranged to coöperate with the pawl, a loom control lever and mechanism intermediate of the tilting pawl and control lever for throwing the control lever into position to stop the loom when the pawl is engaged by the hook.

In testimony, that I claim the foregoing as my invention, I have signed my name in presence of two witnesses, this 11th day of August, 1911.

GEORGE KOCH.
